UNITED STATES PATENT OFFICE.

WILLIAM KELSO, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

CAR COUPLER.

Application filed August 26, 1925. Serial No. 52,645.

The invention relates to car couplers of the type in which a knuckle is rotatably mounted upon the coupler head by means of a pivot pin.

5 The primary object of the invention is to provide strong and simple means efficiently operating to relieve the pivot pin from pulling and buffing stresses when the coupler is in service.

10 The principal feature of the invention consists in providing the head and knuckle of a car coupler with pivot pin openings of such a character that the knuckle is adapted to move in the direction of length of the coupler as 60 well as to rotate with respect to the head, and in forming the knuckle with a circularly curved pulling shoulder which is concentric with one of the openings through which the pivot pin passes, the coupler head being provided with a shoulder curved to conform to 65 said pulling shoulder and adapted to cooperate with the latter when the knuckle is subjected to draft forces.

25 A further feature of the invention consists 70 in mounting the knuckle upon the coupler head in such manner that it may rotate and also slide longitudinally with respect to said head and in providing the knuckle with a circularly curved pulling shoulder and with 75 a buffing shoulder, the said shoulders being in spaced relation and the head being formed with a lug which when the knuckle is closed projects into the space between said shoulders and affords an abutment for cooperating 80 with the pulling and buffing shoulders of the knuckle when the coupler is in service.

30 Other features of the invention residing in 85 advantageous forms of construction and relations of parts will hereinafter appear and be 90 pointed out in the claims.

40 In the drawings showing a preferred embodiment of the invention.

Figure 1 is a view, partly in plan and partly in horizontal section of a portion of a 95 car coupler embodying the invention.

Figure 2 is a view partly in section on the line 2—2, Figure 1 and partly in elevation.

Figure 3 is a sectional view on the line 3—3, Figure 1, the pivot lugs or ears of the 100 coupler head being in elevation.

In the drawings 1 indicates the coupler head or coupler body, 2 is the rotatable knuckle mounted thereon, 3 is the lock by which the outward rotation of the knuckle is 105 normally prevented and 4 is the knuckle

opener. As the particular form of lock and the type of knuckle opener employed are not material to the present invention, only portions of these members have been illustrated. These elements are however preferably of well known types, the lock 3 being a vertically sliding gravity actuated pin and the knuckle opener 4 being a pivoted bell crank lever.

5 The knuckle 2 is movably mounted upon the head 1 so as to be capable of sliding longitudinally of the coupler and also rotating with respect to said head. To permit these movements of the knuckle, the latter is connected to the coupler head 1 by means of a pivot pin 5 extending through suitable openings in the connected parts, at least one of said openings being circular and the remainder being elongated in the direction of length of the coupler. As shown in the drawings the pivot pin hole 6 in the knuckle 70 may advantageously be the elongated one while the pivot pin holes 7 in the ears or pivot lugs 8 of the coupler head may be circular. The pivot pin 5 may be retained in assembled 75 position by means of a cotter 9.

On its upper side and preferably on its under side also, the tail of the knuckle 2 is formed with a circularly curved pulling shoulder 10, which, by cooperating with the correspondingly curved rear face 11 of an overlapping lug 12 integral with the coupler head, serves to relieve the pivot pin 5 from strain when the knuckle is subjected to draft forces. The circularly curved pulling shoulders 10 of the knuckle and the correspondingly curved shoulders 11 of the coupler head with which said pulling shoulders cooperate are concentric with the circular pivot pin openings 7 when the knuckle is in closed position and is resisting pulling.

95 In advance of the pulling shoulders 10 the knuckle 2 is provided on its upper and under side with buffing shoulders 13 which preferably are flat vertical surfaces disposed tangent to the cylindrical hub 14 of the 100 knuckle and extending substantially transversely of the coupler when the parts are in locked position. When the knuckle is closed the pulling shoulders 10 and buffing shoulders 13 assume a position such that they are 105 intersected by a radial line extending from the center of the circular pivot pin openings 7 toward the coupler lock 3, thus efficiently opposing the resultant forces to which the knuckle is subjected in draft and buffing.

The forward face of each of the lugs 12 is formed as a flat vertically extending shoulder 15 for cooperating with the adjacent buffing shoulder 13 of the knuckle.

5 The pivot lugs or ears 8 of the coupler head are preferably stepped or recessed on their peripheral faces, as indicated at 16, so as to have overlapping cooperation with the curved lugs or flanges 17 projecting vertically from the opposite ends of the hub 14 of the knuckle. These flanges 17 by cooperating with the ears of the coupler head assist in relieving the knuckle pin 5 from transverse strain incident to draft forces. In advance 10 of the knuckle pin opening the knuckle may advantageously be provided with oppositely extending circularly curved lugs or flanges 18 adapted to cooperate with the outer curved peripheral portions of the adjacent pivot 15 ears 8 of the coupler head. The inner faces of these lugs 18 together with the faces of the knuckle 2 in vertical alinement therewith cooperate with the corresponding outer faces of the ears 8 of the head and thereby assist in 20 relieving the pivot pin 5 of forces resulting from buffing action. Where the lugs 18 overlap and merge with the flanges 17 the former by cooperating with the pivot lugs 8 also serve to relieve the knuckle pin from transverse strains incident to service.

It will be perceived that the invention affords means for efficiently protecting the knuckle pin of a car coupler against undue strains incident to draft and buffing and that 35 the form and relation of the pulling and buffing shoulders together with the manner of mounting the knuckle upon the coupler head insure extended contact of the pulling and buffing shoulders of the knuckle with the corresponding shoulders of the head and thereby effect distribution of the draft and buffing shocks throughout a relatively large mass of metal.

I claim:

45 1. A car coupler involving a coupler head, a knuckle, a lock for said knuckle, and a pivot pin for movably connecting said head and knuckle, said head and knuckle having openings for receiving said pivot pin, at least one 50 of said openings being circular, said knuckle being adapted to move in the direction of length of the coupler as well as to rotate with respect to said head, said knuckle being provided with a circularly curved pulling shoulder concentric with said circular opening when the knuckle is in closed position and also being provided with a buffing shoulder, said head being provided with a shoulder curved to conform to said pulling shoulder and adapted to cooperate with the latter when the 55 knuckle is subjected to draft forces, and said head also being provided with a shoulder conforming to said buffing shoulder and adapted to cooperate therewith when the 60 knuckle is subjected to buffing forces.

65 2. The pivot lugs or ears 8 of the coupler head are preferably stepped or recessed on their peripheral faces, as indicated at 16, so as to have overlapping cooperation with the curved lugs or flanges 17 projecting vertically from the opposite ends of the hub 14 of the knuckle. These flanges 17 by cooperating with the ears of the coupler head assist in relieving the knuckle pin 5 from transverse strain incident to draft forces. In advance 10 of the knuckle pin opening the knuckle may advantageously be provided with oppositely extending circularly curved lugs or flanges 18 adapted to cooperate with the outer curved peripheral portions of the adjacent pivot 15 ears 8 of the coupler head. The inner faces of these lugs 18 together with the faces of the knuckle 2 in vertical alinement therewith cooperate with the corresponding outer faces of the ears 8 of the head and thereby assist in 20 relieving the pivot pin 5 of forces resulting from buffing action. Where the lugs 18 overlap and merge with the flanges 17 the former by cooperating with the pivot lugs 8 also serve to relieve the knuckle pin from transverse strains incident to service.

pulling and buffing shoulders of the knuckle being spaced from each other and being intersected by a radial line extending from the center of said circular opening toward the knuckle engaging face of said lock when the 70 parts are in coupled relation.

2. A car coupler involving a coupler head, a knuckle, and a pivot pin for movably connecting said head and knuckle, said head and knuckle having openings for receiving said pivot pin, at least one of said openings being circular, said knuckle being adapted to move longitudinally of the coupler as well as to rotate with respect to said head, said knuckle being provided with a circularly curved pulling shoulder concentric with said circular opening when the knuckle is in closed position and also being provided with a buffing shoulder having a flattened portion, said head having a shoulder curved to conform to said pulling shoulder and adapted to cooperate with the latter when the knuckle is subjected to draft forces, and said head also having a shoulder conforming to said buffing shoulder and adapted to cooperate therewith when the 80 knuckle is subjected to buffing forces, said buffing shoulder being located between said pulling shoulder and said pivot pin.

3. A car coupler involving a coupler head, a knuckle, a pivot pin for movably connecting said head and knuckle, said head and knuckle having openings for receiving said pivot pin, at least one of said openings being circular, said knuckle being adapted to move longitudinally of the coupler as well as to rotate with respect to said head, said knuckle being provided with a circularly curved pulling shoulder concentric with said circular opening when the knuckle is in closed position and also having a buffing shoulder provided with a portion extending substantially transverse to the longitudinal axis of the coupler, said head being provided with a shoulder curved to conform to said pulling shoulder and adapted to cooperate with the latter when the knuckle is subjected to draft forces, and said head also being provided with a shoulder conforming to said buffing shoulder and adapted to cooperate therewith when the 100 knuckle is subjected to buffing forces.

4. A car coupler involving a coupler head, a knuckle, and a pivot pin for movably connecting said head and knuckle, said head and knuckle having openings for receiving said pivot pin, at least one of said openings being circular, said knuckle being adapted to slide and rotate with respect to said head, said knuckle having a circularly curved pulling shoulder concentric with said circular opening when the knuckle is in closed position and also having a buffing shoulder in advance of said pulling shoulder, and said head being provided to the rear of said pivot pin with a lug which is adapted to extend between and overlap said shoulders, the rear face of said 115 120 125 130

lug being curved to conform to said pulling shoulder and the forward face of said lug conforming to said buffing shoulder and cooperating therewith to resist buffing force.

5 5. A car coupler involving a coupler head, a knuckle, and a pivot pin for movably connecting said head and knuckle, said head being provided with ears having circular openings for receiving said pivot pin, said knuckle 10 having an elongated opening for receiving said pivot pin, said knuckle being provided with a circularly curved pulling shoulder concentric with said circular openings when the knuckle is in closed position and also being 15 provided with a buffing shoulder in advance of said pulling shoulder, and said head being provided with a lug extending between said pulling and buffing shoulders of the knuckle, the rear face of said lug being curved to con-

form to said pulling shoulder and the forward 20 face of said lug conforming to said buffing shoulder and cooperating therewith to resist buffing force.

6. A car coupler involving a coupler head, a knuckle having a perforated hub and a tail 25 extending rearwardly from said hub, and a pivot pin for movably connecting said head and knuckle, the hub of said knuckle having an elongated opening for receiving said pivot pin, said knuckle being provided with a 30 buffing shoulder having a portion tangent to said hub, and said head being provided with a shoulder conforming to said buffing shoulder and adapted to cooperate with the latter when the knuckle is subjected to buffing 35 forces.

In testimony whereof I affix my signature.
WILLIAM KELSO.
